BIRD CAGE

Marcel M. Arnould, East Orange, N. J.

Application May 14, 1953, Serial No. 25,009

Term of patent 14 years

(Cl. D31—2)

To all whom it may concern:

Be it known that I, Marcel M. Arnould, a citizen of the United States, residing at East Orange, in the county of Essex and State of New Jersey, have invented a new, original, and ornamental Design for a Bird Cage, of which the following is a specification, reference being had to the accompanying drawing, constituting a part hereof.

Fig. 1 is a perspective view of a bird cage, showing my new design;

Fig. 2 is a side elevational view thereof; and
Fig. 3 is a front elevational view thereof.

I claim:

The ornamental design for a bird cage, substantially as shown.

MARCEL M. ARNOULD.
